ELASTIC FLUID TURBINE ARRANGEMENT

Oscar Junggren, deceased, late of Schenectady, N. Y., by the Schenectady Trust Company of Schenectady, N. Y., executor, assignee to General Electric Company, a corporation of New York

Application June 26, 1936, Serial No. 87,556

7 Claims. (Cl. 253—69)

The present invention relates to elastic fluid turbine arrangements including a high pressure turbine and a low pressure turbine or turbines arranged in tandem, more specifically to tandem-compound-double-flow-turbines including a high pressure turbine and a double flow low pressure turbine receiving steam from the high pressure turbine and having shafts in alignment and coupled together. Difficulties are often experienced with this type of turbine arrangements, due to their considerable length when the available floor space is limited.

The object of the invention is to provide an improved construction and arrangement of tandem compound turbines whereby the manufacturing cost is reduced and a compact design attained, necessitating comparatively little floor space. This and other objects of the invention are accomplished by the provision of a fabricated turbine casing for at least a portion of the high pressure turbine and a portion of the low pressure turbine together with the provision of a bearing for supporting the shaft between the two turbines, which bearing is completely enclosed by the casing. In a preferred embodiment, such bearing has one side exposed to the elastic fluid discharged from the high pressure turbine and another side exposed to the elastic fluid exhausted from the low pressure turbine.

A preferred arrangement is illustrated in the accompanying drawings, in which Fig. 1 is a sectional view through a turbine arrangement embodying the invention; Fig. 2 is a section along the lines 2—2 of Fig. 1; Fig. 3 is a section along line 3—3 of Fig. 1; and Fig. 4 is a perspective view of the arrangement of Figs. 1 to 3.

The arrangement as best shown in Fig. 4 comprises a high pressure turbine or turbine part 10 and a double flow low pressure turbine or turbine part 11 receiving elastic fluid discharged from the high pressure turbine through a channel or cross-over conduit 12. The double flow turbine has an exhaust casing comprising an upper portion 13 and a lower portion 14 secured together by means including flanges 15. The upper portion 13 is provided with port holes 16, 17. Another port hole 18 is provided for the cross-over channel 12.

Referring now to Fig. 1, the casing of the high pressure turbine 10 includes an inlet portion 20 and an outlet portion 21. The latter is manufactured from a steel ring provided with grooves 22 for holding a plurality of diaphragms 23. The high pressure portion 20 has a flange 24 which is secured by means of a plurality of bolts 25 to

a ring 26 forming a flange for the outlet portion 21 and being secured thereto by a weld 27. The rotor of the high pressure turbine comprises a shaft 28 carrying a plurality of bucket wheels 29 and supported on the discharge side of the turbine by a bearing 30.

The low pressure turbine which in the present instance is in the form of a double flow turbine 11 has a casing comprising inlet portions 31 and 32 facing each other and outlet portions 33 and 34 secured by bolts 35 and 36 to the inlet portions 31 and 32, respectively. The inlet casing portions 31 and 32 have recesses 37 and 38, respectively, in their outer surfaces for positioning wall members or partitions 39 and 40, respectively. These partitions 39 and 40 together with a curved outer wall 41 welded to their outer edges form an annular inlet chamber 42 for the double flow turbine. The rotor of the latter comprises a shaft 43 with a plurality of bucket wheels 44 secured thereto. The left-hand end of the shaft 43 is fastened to the end of the shaft 28 by suitable coupling means 45 and the right-hand end of the shaft 43 is secured by similar coupling means 46 to a shaft 47, which latter forms a part of an electric generator driven by the turbines. The shaft 47 is supported on a bearing 48. The double flow turbine exhausts in opposite directions. The exhaust casing for receiving exhaust fluid is completely fabricated and comprises, as pointed out above, an upper portion 13 and a lower portion 14 united by flanges 15. The upper portion 13 has a cylindrical wall portion 49, a left-hand wall portion 50 and a right-hand wall portion 51 united by fused metal, preferably welds. In addition, the exhaust casing includes the aforementioned partitions or wall members 39 and 40. The lower portion 14 of the exhaust casing has side walls 52 and 53 and front and rear walls 54 (Figs. 2 and 4). Elastic fluid discharged from the high pressure turbine is conducted to the low pressure turbine by the channel 12, which, in accordance with the invention, has wall portions partly defined by the exhaust casing. The common wall portions of the exhaust casing and the channel or crossover conduit 12 include the left-hand side wall 50, the outer curved wall 49 and an extension of the partition 40. In addition, the channel 12 includes front and rear walls 55 (Fig. 4), a left-hand end wall 56 and an outer curved wall 57 concentrically arranged with; that is, uniformly spaced from, the inner curved wall 49. It is important to note that all these wall elements are fabricated and united by fused metal, preferably

welds. In addition, the channel 12 includes front and rear walls 55 (Fig. 4), a left-hand end wall 56 and an outer curved wall 57 concentrically arranged with; that is, uniformly spaced from, the inner curved wall 49. It is important to note that all these wall elements are fabricated and united by fused metal, preferably

welds. The channel is reinforced by a partition 58, which is welded to the walls 50, 49, 51, 56 and to an upper portion of the bearing 30. Not all of the fluid discharged from the high pressure 5 turbine is conducted from the crossover conduit 12 to the low pressure turbine. It is desirable to separate water from the fluid discharged from the high pressure turbine and in many cases, it is also desirable to extract part of the elastic 10 fluid. To this end, the crossover conduit 56 is provided with a downward extension. The lower portion of the conduit is formed by a curved wall member 59 (Fig. 4) with an opening 60 in its bottom portion, which latter communicates with 15 a conduit 61. The major portion of liquid and also a portion of the elastic fluid discharged from the high pressure turbine may be removed from the crossover conduit through the conduit 61. Some of the fluid discharged from the high pressure 20 turbine is forced in upward direction. In order to prevent condensate from flowing back into the path of fluid discharged from the turbine and being carried over to the low pressure turbine, a collecting channel 62 is provided with regard 25 to the outlet end of the upper half of the high pressure turbine casing. This collector channel 62 is secured to the discharge portion 21 of the high pressure casing by means including a plurality of bolts 63. Liquid particles collected in 30 the channel 62 flow downward in said channel and are discharged through the opening 60 into the conduit 61.

Another important feature of the invention is 35 the bearing arrangement. Both bearings 30 and 48 are rigidly secured to and supported on the fabricated walls of the exhaust casing. Both bearings have a portion disposed within the exhaust casing; that is, exposed to the fluid therein. In addition, the bearing 30 has another portion 40 adjacent the high pressure turbine disposed within the discharge space of the high pressure turbine, hence exposed to the fluid therein. The discharge pressure of the high pressure turbine usually is above atmosphere, whereas the 45 exhaust pressure of the low pressure turbine usually is below atmospheric pressure. In order to prevent elastic fluid from entering the bearing 30, both ends of this bearing are provided with packings 64 which may include both labyrinth 50 and water sealing elements. Such complete packing or sealing arrangement is provided also with regard to one side of the packing 47 disposed within the exhaust space of the low pressure 55 turbine. The other side of the bearing 47 in the present instance is provided with a simpler packing arrangement 65. The bearing arrangement just described reduces considerably the length of the shaft of the low pressure turbine and, what is more important, it reduces the over-all 60 length of the entire turbine arrangement, hence necessitating comparatively small floor space. The reduction of necessary floor space is further attained by supporting the casing of a generator to be driven by the turbine arrangement at least partly on the exhaust casing of the low pressure turbine. To this end the right-hand 65 end wall 51, 53 of the low pressure turbine is provided with an extension 66 having a flange 67 for supporting a generator casing. 70 Summarizing, an improved turbine arrangement including high pressure and low pressure turbine means arranged in tandem is attained by providing the bearing means between the high pressure and low pressure turbine within the exhaust space of the two turbines. The casing of 75

the low pressure turbine is completely fabricated and portions of the casing serve as a support for the turbine bearing or bearings. The crossover conduit or channel for conducting elastic fluid from the high pressure to the low pressure turbine 5 is also completely fabricated and includes walls forming portions of the exhaust casing of the low pressure turbine. The casing of both the high pressure and the low pressure turbines form in substance a single, unitary structure. From another viewpoint, both turbines have a single casing with the bearing for supporting the shaft or shafts of the intermediate high pressure and low pressure turbines disposed within the elastic fluid space. With the exception of the bolting 10 joint on the high pressure casing part, the casing of the two turbines is integral. A portion of the fluid discharged from the high pressure turbine is extracted by means including a conduit connected to a downward extension of the 15 crossover conduit. The upper portion of the exhaust end of the high pressure turbine carries a collecting channel for receiving liquid discharged from the last stage of the high pressure turbine. This collector channel has a flaring 20 portion which directs the elastic fluid upward. The outer surface of the channel forms a groove for collecting any water dropping back and preventing such water from dropping into the elastic fluid flowing from the high pressure to the 25 double-flow low pressure turbine. The exhaust casing of the low pressure turbine has an extension for supporting an electric generator casing to be driven by the turbines.

Having described the method of operation of 35 the invention, together with the apparatus which it is considered represents the best embodiment thereof, it is desired to have it understood that the apparatus shown is only illustrative and that the invention may be carried out by other means. 40

What is claimed as new and desired to be secured by Letters Patent of the United States is:

1. A turbine arrangement including the combination of a high pressure turbine, a low pressure turbine, shaft means for the turbines, a 45 bearing for supporting the shaft means, said bearing having one side disposed in the exhaust space of the high pressure turbine and another side disposed in the exhaust space of the low pressure turbine, and packing means on each side 50 of the bearing to reduce leakage of exhaust fluid from the high pressure turbine into the bearing and from the latter into the low pressure turbine.

2. A turbine arrangement including the combination of a high pressure turbine, a low pressure 55 turbine in alignment with the high pressure turbine, shaft means for the turbines, an exhaust casing for the high pressure turbine having a wall adjacent the low pressure turbine, a crossover conduit including said wall for conducting fluid 60 discharged from the high pressure turbine to the low pressure turbine, a bearing for supporting the shaft means, said bearing being supported by said wall and having portions disposed within the exhaust spaces of both turbines, and means sealing 65 said bearing.

3. A turbine arrangement including a high pressure turbine and a double flow low pressure turbine having a fabricated exhaust casing, a crossover conduit for conducting elastic fluid 70 from the high pressure turbine to the double flow turbine, said crossover conduit having walls partly defined by the exhaust casing, and shaft bearing means partly disposed within the crossover conduit.

4. A turbine arrangement including a high pressure turbine and a double flow low pressure turbine arranged in tandem, shaft means for the turbines, a bearing for supporting the shaft means, a fabricated exhaust casing for the double flow turbine having a wall intermediate the turbines for supporting said bearing, and means including said wall for defining a crossover conduit between the turbines, said bearing having one side disposed in the exhaust space of the high pressure turbine and another side disposed in the exhaust space of the double flow turbine.
5. A turbine arrangement including a high pressure turbine and a double flow low pressure turbine for receiving elastic fluid discharged from the high pressure turbine, said double flow turbine having a fabricated exhaust casing including a wall portion defining a crossover conduit between the high pressure and the double flow turbine and another wall portion with an extension for supporting a generator to be driven by the turbines, and a shaft bearing supported on the other wall portion and partly disposed within the exhaust of the double flow turbine.
6. A turbine arrangement including a high pressure turbine, a double flow low pressure turbine for receiving elastic fluid discharged

from the high pressure turbine, said turbines having a single fabricated casing and a crossover conduit between the high pressure turbine and the double flow low pressure turbine, said crossover conduit having a portion surrounding the 5 exhaust end of the high pressure turbine and being secured to an adjacent wall of the double flow turbine.

7. A turbine arrangement including a high pressure turbine, a double flow low pressure turbine for receiving elastic fluid discharged from the high pressure turbine, said turbines having a single casing defining a crossover conduit between the high pressure turbine and the double flow low pressure turbine, and a flaring channel 15 member disposed within the crossover conduit and extending over about 180 angular degrees for upwardly directing elastic fluid discharged from the high pressure turbine and for preventing condensate from dropping back into the elastic fluid discharged from the high pressure turbine.
